FIG. 1

FIG. 2

INVENTOR,
JOHN A. BURNHAM
BY

Mitchell, Chaderick & Kent

ATTVS.

UNITED STATES PATENT OFFICE.

JOHN A. BURNHAM, OF WENHAM, MASSACHUSETTS.

TWINE-HOLDER.

1,244,418.

Specification of Letters Patent. Patented Oct. 23, 1917.

Application filed January 3, 1916. Serial No. 69,737.

To all whom it may concern:

Be it known that I, JOHN A. BURNHAM, a citizen of the United States, residing at Wenham, in the county of Essex and State 5 of Massachusetts, have invented new and useful Improvements in Twine-Holders, of which the following is a specification.

This invention relates to improvements in twine holders. More particularly it relates 10 to improvements in mechanical devices whose attributes are such that they are available for use as mechanical or function-serving elements in devices intended to be of esthetic as well as of practical value. Countless types of twine holders have heretofore 15 been known to the public, or suggested for manufacture, which are without exception lacking in availability for use in any construction that is desired to have esthetic merit, or in one having that combination of 20 beauty and utility which it is intended by the present invention to make possible. For example, the ordinary cast iron grating twine-ball-cage looks out of harmony and discordant in a place, such as a gift shop, 25 tea-room or room in a home where the other surroundings are pleasing to the eye. It is a purpose of the present invention to provide means which are adaptable for use with various ornamental designs to hold balls of 30 twine of various size or shape effectively, so far as the function of holding the twine is concerned, and with some advantages not possessed by any structure heretofore known 35 to me such as adaptability to different designs of twine holding devices, adaptability in the esthetic sense to harmonize with and form a part of such designs in form and in color, and adaptability to differing sizes of 40 ball. The invention relates more especially to the part of the twine holder which is immediately in contact with the ball of twine. The objects of the invention are accomplished by providing ball retaining projections in the form of pliant sheet metal 45 fingers which can be molded into the desired shape, preferably in three dimensions, which when so molded are sufficiently stiff to hold the twine and which yet are sufficiently flexi-

ble to permit of being shifted in form or 50 position in accordance with the art of the designer or the needs of the user, and which, because of these characteristics can be made a part of a design whose greater part is 55 executed in the base supporting the said ball retaining projections. One embodiment of the invention is illustrated in accompanying drawings, but it is to be understood that the invention may be embodied in a multitude 60 of forms within the scope of the appended claims, of which this is only one illustration. It is intended that the patent shall cover by suitable expression in the appended claims whatever features of patentable novelty are 65 disclosed herein.

In the accompanying drawings:

Figure 1 is a side elevation of a twine holder partly in section;

Fig. 2 is a plan of the same with parts removed and with other parts changed in 70 position.

Referring to the drawings, 10 indicates a plinth adapted to rest horizontally on a counter or table, and 11 an upright piece held thereby. Each of these may conveniently be made by sawing from a board, the part 11 resting edgewise on the part 10 and being secured thereto by screws 12 or by any other suitable means. They may, however, be made in any other suitable way, as by 80 casting in plaster or metal. The part 11 is represented as being cut and painted so as to represent by form and coloring a flower basket or an urn *c* containing tulips, the leaves *a* of which are seen, and the stems *b* 85 in conventional design. While the drawing shown herein is wholly in black and white owing to the limitations of rules affecting patents, the article itself may be colored, as indeed is indicated by the conventional representation 13 of green upon the leaves *a* and stems *b*. Forming a part of this design, and growing out of it, as it were, are the ball retainers, of which three are shown, each in this instance representing a calyx, 90 and each being held by a screw 14 upon a base consisting of one of the conventional stems *b* of the design into which the wooden 95

support 11 is made. Each of these twine holders consists of a piece of soft metal, for which I have found lead suitable, but for which any sufficiently pliable and at the same time sufficiently stiff metal, alloy or composition can be used. These pieces are cut from a blank sheet in substantially the shape shown at the right in Fig. 2 where one of them is represented as having been opened from the finished form of the others into a nearly flat form. Having been originally cut into this form the individual projecting sections may be shaped by pressure of one's fingers into the concave and more or less spherical form indicated by the shadings at the right in Fig. 2 and by the shapes shown in the other parts of the drawing and then may be bent up together to form the holder, supported on the end of a stem *b* and extending in the same general direction. In this the interior of the sheet of metal approximates the shape of a ball of twine, and the ball retaining projections become stiffer because of their curvature in three dimensions. The projecting sections 15 may then be painted as a part of a whole design including the wooden support 11, parts of which become the leaves *a*, the stems *b*, and the urn *c*, the projecting section 15 in this instance becoming sepals. In use, a ball of twine may be set in, the sepals upon the same being bent open enough for the purpose, and then may be gripped by pressing the sepals back against the ball as indicated at the right in Fig. 1, where the point of one of the sepals is seen to have been pressed a little into the ball of twine. This holds the ball with sufficient firmness. Ordinarily twine is drawn from the center of such a ball and the position does not need to be frequently changed, but when the ball is sufficiently exhausted the sepals can be bent in to any desired degree so as to hold the remnants of the ball, after which they may be bent out and a fresh ball inserted.

A particular characteristic to which attention is directed is the fact that these twine retaining projections which are marked 15 in the drawing can with the greatest ease be cut by the maker to harmonize with any design which he may happen to prefer. A design of tulips is shown, in which the green of the leaves and of the sepals, blends with the color of the ball of twine, which may be selected to be held by it, thus producing a holder which is both graceful and of proven commercial value. However, the design might be made with rose leaves or lilies, in which case the lead twine retaining projections 15 would be shaped variously, in harmony with the design, but would serve equally well their function of holding the twine. Or the de-

sign might be that of some other idea not at all drawn from plant life. The particular design forms no part of the invention, the idea being that the invention is adaptable for use in making a multitude of different designs.

While it is deemed convenient to cut all of the retaining fingers in one calyx from a single sheet of metal, they obviously might be made separately. If the lead breaks with excessive bending, or if for other reason it is desired to do so, this part of the whole can be easily replaced by a fresh one, upon removal of the screw 14.

I claim as my invention:—

1. A twine holder having members adapted conjointly to hold a ball of twine, comprising a base and said members projecting from the base and supported only thereon; the members being individually broad, having curvature in three dimensions of space, being bendable to and from their ball-holding positions, and having sufficient stiffness to remain in the positions to which they are thus bent.

2. A twine holder comprising a combination of a base and a single sheet of metal fastened thereto, said sheet being cut with sundry portions projecting from all sides of a central portion and being of pliable material capable of being bent by human fingers into curvature of three dimensions and having sufficient stiffness to remain in the positions to which they are thus bent.

3. A twine holder having projecting twine holding members of broad material individually sufficiently pliant to be bent by human fingers and thus curved in three dimensions; and a support to which the said members are attached.

4. A twine holder having projecting members of sheet lead adapted to engage a ball of twine on various sides; a support therefor; and attaching means.

5. A twine holder having projecting members of pliant broad material adapted to engage and hold twine; a support therefor; the combination of said support and said members constituting a continuous ornamental design, part of which is rigid and part of which is variable by human fingers by the pliancy of said members.

6. A twine holder having projecting non-elastic members of pliant material; a support therefor; the said members being attached to the support, and adapted to engage and hold twine; the individual members being sufficiently pliant so that one part thereof can be moved by the human fingers into different relation to the other parts of the same member and sufficiently stiff to retain such position.

7. A twine holder comprising a solid support having a part projecting in a definite

direction combined with multiple, pliable, sheet continuations thereof extending in the same general direction on various sides of its axis and capable of being moved toward and 5 from the axis to hold or release the ball of twine, the said projecting support being rigid, and the continuations rigidly attached thereto, and the said holding or releasing

movement being effected by flexure of the said sheet continuations thereof. 10

Signed by me at Boston, Mass., this 24th day of December, 1915.

JOHN A. BURNHAM.
